UNITED STATES PATENT OFFICE.

CONRAD DRESSLER, OF CLEVELAND, OHIO, ASSIGNOR TO AMERICAN DRESSLER TUNNEL KILNS, INC., OF CLEVELAND, OHIO, A CORPORATION OF NEW YORK.

TUNNEL KILN.

Application filed June 12, 1923. Serial No. 645,217.

My present invention relates to tunnel kilns and particularly to tunnel kilns of the open fire type which are heated by burning gases and hot products of combustion passing into the kiln chamber proper from fire boxes or combustion chambers at the sides of the kiln; and the object of my invention is to improve the fire box constructions of such kilns and particularly to make simple and effective provisions for cooling the walls of the combustion chambers of such fire boxes and at the same time highly preheating the air applied to the combustion chambers to support combustion therein and supplying it to said chamber to secure efficient combustion therein.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated a preferred embodiment of my invention.

Of the drawings:

Fig. 1 is a diagrammatic plan view of a tunnel kiln;

Fig. 2 is a section on the line 2—2 of Fig. 1;

Fig. 3 is a section on the line 3—3 of Fig. 2;

Fig. 4 is an elevation of the grate and ash removing means employed; and

Fig. 5 is a partial section on the line 5—5 of Fig. 3.

In the drawings A represents a tunnel kiln comprising a preheating zone *a*, high temperature or firing zone *b*, and cooling zone *c*. The kiln is heated by hot products of combustion and burning gases passing into the kiln chamber proper from the fire boxes B suitably distributed along the sides of the high temperature or firing zone *b* of the kiln. The products of combustion are withdrawn from the kiln chamber adjacent the entrance end of the latter by the stack C.

Each fire box B is a masonry structure comprising a combustion chamber B' open at its inner end to the kiln chamber through a port B² in which checker brick R may be stacked. Each fire box is formed at its outer end with a fuel charging port B³ normally closed by a door D. The combustion

chamber B' is provided with a depending portion B⁴, adjacent its outer end, in the lower portion of which is mounted the grate E on which the fuel is burned. Advantageously, though not necessarily, the grate E is of the type shown and comprises a metallic frame member E' on which is secured tubular end members E² and U shaped grate members E³ proper, which are spaced apart to provide outlets E⁴ for air supplied through one of the tubular members E² and the pipe F connected to the outer end of the latter. The outer end of the other tubular member E² is closed, as by the cap E⁵. Mounted on the frame member E' are sprocket wheels G over which run ash removing sprocket chains G'.

To cool the walls of each fire box, and thereby prevent those walls from being injured by overheating and at the same time to highly preheat the air supporting combustion provisions are made for passing such air through cooling channels in the fire box walls. These channels include a channel H formed in the wall surrounding the port or throat B², through which the combustion chamber proper communicates with the interior of the kiln. As shown the channel H surrounds the port B², and receives air at its underside through a port H' from a subjacent flue I running lengthwise of the kiln at the corresponding side of the latter. From the top of the channel H, the air passes through a pipe J into an air chamber or channel K which envelops the sides and top of the combustion chamber proper, the combustion chamber being formed with double side and top walls to provide for the chamber K. The lower ends of the chamber K, which is in the shape of an inverted U, are divided into flues K' by masonry walls or ribs K², which give mechanical stability to the inner wall of the chamber K. The lower ends of the flues K' at each side of the combustion chamber are connected to a corresponding horizontal flue K³. The two flues K³ are each connected to a channel L which passes under the charging port B³. The channel L is connected at one side of the fire box to the pipe F supplying air to the hollow grate, and the air thus supplied to the hollow grate forms the primary air of combustion for the fuel on the grate. The channels K also supply air to a cross channel LA the top and side walls of which

105

110

form a bridge wall in the combustion chamber B', in front of the depending port B⁴ thereof. The secondary air for combustion is supplied to the combustion chamber B' from the cooling system through suitable ports L⁵, M, and N. As shown the ports L⁵ are lead from the top of the channel LA, the ports M are located in the roof and side walls of the combustion chamber and receive air from the chamber K and its extensions K', and the ports N are located in the outer end wall of the combustion chamber at the sides of the charging port B³ and receive air from vertical branches L' of the channel L at the sides of the charging port B³, and each provided with a regulating damper L⁴.

The air supplied to the fire box cooling channels through the flues I may advantageously be air which has already been heated to some extent, and for this purpose I preferably employ air previously heated in cooling the ware in the cooling zone of the kiln or in cooling the tracks and under structure of the cars. In the construction illustrated, the air is furnished under suitable pressure by a fan P which draws heated air from the cooling zone section e of the kiln. The fan may draw air directly from the kiln chamber, or from cooling flues in the walls of the kiln chamber as in the kiln arrangement shown in the application of Paul A. Meehan, Serial No. 645,310, filed June 14, 1923. By the preliminary heating of the fire box cooling air, it is possible to obtain the desired cooling effect, and the desired amount of preheated air for supporting combustion without an undue cooling effect in the walls of the channel H into contact with which the cooling air first comes.

With the described arrangement in which the cooling air first flows through the channel H along the underside of the throat or port B², and thence up at the opposite sides of that port in divided streams which meet above the port, and is then passed into the top of the chamber K and passes downward through the legs of the latter to the channel L, a uniform and adequate cooling effect is obtained, and the air is properly preheated for use in combustion. It will be observed that the cooling air is at its lowest temperature when it enters the channel H where the most drastic cooling effect is desired.

The preheating of the air for secondary combustion and the manner in which this air is introduced into the combustion chamber increases the efficiency of combustion by effecting a proper intermingling of the combustible gases rising from the fuel bed and the prompt ignition of the mixture thereby making effective use of the whole chamber B as a combustion chamber, and tends to the complete combustion of the fuel in the com-

bustion chamber. The prompt and thorough intermingling of the combustible gases with the air for combustion is insured by the comparatively large number of secondary air admission ports L⁵, M, and N, and the wide distribution of these ports over the wall of the combustion chamber. The jets discharged through these ports set up whirls and eddies in the gases passing through the combustion chamber which aid in the rapid and thorough admixture of the gases. This mixing effect may be enhanced to advantage in some cases by a special disposition of the ports M to increase their gas whirling effect. The complete combustion of the fuel in the combustion chamber is especially desirable as it avoids the inequalities in the heating effects produced in the kiln chamber which result from burning a portion of the fuel gases therein. With the described arrangement in which practically all of the highly heated walls of the combustion chamber, and of the port B are directly cooled by the air passages H and J, the secondary air supply ports L⁵, M, and N, can be located wherever experience, or the conditions of operation for any particular kiln burning any particular kind of fuel, make it desirable to locate such ports. By means of the dampers J' and F' in the pipes J and F, respectively, the amounts of primary and secondary air supplied may be readily and separately controlled, thus permitting of an easy and accurate regulation of the rate of combustion and the character of combustion, since by varying the relative amounts of primary and secondary air supplied, the gases passing from the combustion chamber into the kiln chamber may be made oxidizing, neutral or reducing.

The provision of the ports N at the sides of the charging port B³ is especially important in view of the manner in which the fire boxes of the kiln illustrated are ordinarily charged. In charging such fire boxes with coal, some of the fresh coal is left on the bottom wall of the port at each charging operation. This coal is partially distilled by the heat in the fire box before the following charging operation occurs, at which time the coke-like residue of the coal previously left on the bottom wall of the charging port is pushed on to the fuel bed and a new supply of fresh coal is left on the bottom wall of the port. With ports N arranged as shown, the gases of distillation from the coal in the port B³ are mixed with air and burned as they are generated. Advantageously the ports N at the opposite sides of the charging port B³ converge toward one another as shown in Fig. 5. This facilitates the rapid ignition and thorough combustion of the said gases of distillation.

While the invention in the form illus-

trated is of especial utility in connection with fire boxes heated by the combustion of solid fuel, the invention in its broader aspects is not restricted to fire boxes burning any particular fuel but may be employed with suitable changes in form with fire boxes heated by the combustion of gas or oil.

While in accordance with the provisions of the statutes, I have illustrated and described the best forms of my invention now known to me, it will be apparent to those skilled in the art that many changes in form may be made without departing from the spirit of my invention, and that certain features of my invention may sometimes be employed to advantage without a corresponding use of other features.

Having now described my invention, what I claim as new and desire to secure by Letters Patent, is:

1. In an open fire kiln having a fire box at the side of the kiln chamber with a combustion chamber therein and a port opening from said combustion chamber to the kiln chamber, the improvement which consists in cooling channels in the walls of said port and at the sides and top of said combustion chamber, and provisions for passing air through said channels into said combustion chamber to support combustion therein.

2. In an open fire kiln having a fire box at the side of the kiln chamber with a combustion chamber therein and a port opening from said combustion chamber to the kiln chamber, the improvement which consists in cooling channels in the walls of said port and at the sides and top of said combustion chamber, ports opening from said channels directly to the combustion chamber to supply secondary air of combustion thereto, and means for passing a portion of the air from said channels to the combustion chamber to serve as primary air of combustion therein.

3. In an open fire kiln having a fire box at the side of the kiln chamber with a combustion chamber therein and a port opening from said combustion chamber to the kiln chamber and primary and secondary air inlets, the improvement which consists in cooling channels in the walls of said port and at the sides and top of said combustion chamber and provisions for passing air through said channels into said inlets in regulated proportions, ports opening from said channels directly to the combustion chamber to supply secondary air of combustion thereto, and means for passing a portion of the air from said channels to the combustion chamber to form a primary air of combustion therein.

4. In an open fire kiln having a fire box at the side of the kiln chamber with a combustion chamber therein and a port opening from said combustion chamber to the kiln chamber, the improvement which consists in

a channel in the wall surrounding said port, a second channel in the wall surrounding the combustion chamber and means for passing air in series through said channels into said combustion chamber.

70

5. In an open fire kiln having a fire box at the side of the kiln chamber with a combustion chamber therein, a port opening from said combustion chamber to the kiln chamber, and a fuel grate in said combustion chamber, the improvement which consists in a channel in the wall of said port, a cooling space in the wall of the combustion chamber, ports opening to the combustion chamber above the fuel grate from said space, a damper controlled connection between the channels, means for supplying air under pressure to the first mentioned channel and a damper controlled connection from the last mentioned channel to the combustion chamber at the underside of the fuel grate therein.

75

6. The combination in an open fire kiln of a fire box at the side of the kiln chamber with a combustion chamber therein, a port opening from said combustion chamber to the kiln chamber, a charging port at the front end of the combustion chamber and a door normally closing said charging port, a fuel grate in the lower portion of the combustion chamber onto which fuel may be pushed through said charging port, cooling channels for the walls of the combustion chamber comprising portions in the front wall adjacent said charging port and outlets therefrom adapted to discharge jets in proximity to said port for burning the gases distilled from coal in said port, and means for supplying air under pressure to said channels.

90

7. The combination in an open fire kiln of a fire box at the side of the kiln chamber with a combustion chamber therein, a port opening from said combustion chamber to the kiln chamber, a charging port at the front end of the combustion chamber and a door normally closing said charging port, a fuel grate in the lower portion of the combustion chamber onto which fuel may be pushed through said charging port, cooling channels for the walls of the combustion chamber comprising portions in the front wall adjacent said charging port and outlets therefrom adapted to discharge jets in proximity to said ports for burning the gases distilled from coal in said port, and means for supplying air under pressure to said channels said outlets being shaped to deliver converging jets at the opposite sides of said charging port.

95

8. In an open fire kiln having a fire box at the side of the kiln chamber with a combustion chamber therein, a port opening from said combustion chamber to the kiln chamber and a fuel grate in said combustion chamber,

100

- tion chamber, the improvement which consists in a bridge wall extending across said combustion chamber between said grate and port, a cooling space in the wall of the combustion chamber including a channel in said bridge wall, and ports distributed along the length of said channel, opening from the latter to said combustion chamber.
9. In an open fire kiln having a fire box
- 10 at the side of the kiln chamber with a combustion chamber therein, a port opening from said combustion chamber to the kiln chamber, and a fuel grate in said combustion chamber, the improvement which consists in
- 15 an air space in the highly heated walls of said chamber, and a multiplicity of small and widely distributed ports through which secondary air of combustion may pass into said chamber from said spaces.
10. In an open fire kiln having a fire box 20 at the side of the kiln chamber with a combustion chamber therein and comprising a thickened wall portion between the kiln chamber and the lower portion of the combustion chamber and having a port opening 25 from said combustion chamber to the kiln chamber above said thickened wall portion, the improvement which consists in a cooling space in the wall of the combustion chamber including a channel in the upper portion of 30 said thickened wall portion and ports distributed along the length of said channel opening from the latter to said combustion chamber.

Signed at Cleveland in the county of 35 Cuyahoga and State of Ohio this 8th day of June, A. D. 1928.

CONRAD DRESSLER.
